WINDOW LOCK AND ALARM

Frederick Piper, Portland, Oreg.

Application September 11, 1937, Serial No. 163,475

2 Claims. (Cl. 116—16)

This invention relates to a combined window lock and alarm, the general object of the invention being to provide means for preventing the sashes of a window being opened from the exterior of a building and also to sound an alarm if an attempt is made to so open the sashes.

Another object of the invention is to provide means whereby the device can be adjusted so that the sashes can be partly opened for ventilating purposes without interfering with the intended operation of the device.

The invention also consists in certain other features of construction, combination and arrangement of the several parts, to be herein after fully described, illustrated in the accompanying drawings and specifically pointed out in the appended claims.

In describing the invention in detail, reference will be had to the accompanying drawings where-in like characters denote like or corresponding parts throughout the several views, and in which:—

Fig. 1 is a fragmentary perspective view showing the invention in place on a window.

Fig. 2 is a longitudinal sectional view of the device.

Fig. 3 is a side view of the housing with the channel member in section.

Fig. 4 is a front view with the housing in section, to show the interior parts.

Fig. 5 is a section on line 5—5 of Fig. 2.

Fig. 6 is a view of the sliding brake member.

Fig. 7 is a view of the clapper member.

In these drawings, the numeral 1 indicates an elongated channel member having a longitudinal row of spaced transversely extending slots 2 in its bottom part, the flanges of the member being bent inwardly. This member is fastened to the inner face of a side rail of the upper sash, as shown in Fig. 1. The numeral 3 indicates a housing, the inner edges of the sides of which are bent outwardly to form the flanges 4 which engage in the guideways formed by the bent flanges of the member 1. Thus the housing is slidably supported by the member 1 and can be removed therefrom by lifting the housing upwardly through the upper end of the member 1. The upper end of the housing has a catch forming projection 5 thereon for engaging any one of the slots 2, the housing having a loose fit in the channel member for enabling the housing to be lifted sufficiently to disengage the catch from one slot and then moved to place the catch in another slot. When the catch is engaging a slot the housing is held against sliding move-

ment, and must be lifted to the position shown in Fig. 3 to free the catch from a slot before it can be moved either upwardly or downwardly.

The upper part of the housing is enlarged, as shown, and the lower part slopes downwardly and inwardly towards the sash and this lower part has a longitudinally extending slot 6 in its front wall. The bottom 7 of the housing is flat and is flush with the flanges 4. The sloping lower part of the housing forms a wedge which is engaged by the top of the lower sash, when either sash is moved towards the other sash, to stop such movement, after the sash is moved a limited amount.

A shaft 8 is journaled in the side walls of the enlarged part of the housing and has one end extended to receive the handle part 9. A spring motor 10 is located in the housing and one end of the spring of the motor is connected with the shaft, so that by turning the shaft in one direction the spring will be wound. This motor rotates a toothed wheel 11 through means of a pawl 12 and ratchet 13, as shown in Fig. 2, the wheel being supported by the shaft 8. The wheel 11 meshes with a pinion 14 on a shaft 15, in the housing and said shaft carries a wheel 16 having the projections 17 on its periphery, each projection having a straight front edge and a beveled rear edge, as shown in Fig. 2.

A brake member 18, shown in Fig. 6 in detail, is slidably arranged in the housing and is supported for sliding movement by the clips 19. The lower end of this member is bent at right angles to form the finger 20 which passes through the slot 6 and its upper end has an off-set projection 21 thereon for engaging the projections 17 on the wheel 16 when the member 18 is in lowered position. As shown in Fig. 2, when the member is in lowered position the straight side or edge of a projection 17 will engage the part 21 and thus the wheel 16 is held against turning movement by the spring motor. However, when the member 18 is in raised position the part 21 is raised above the path of movement of the projections and the wheel 16 can be rotated from the spring motor. A clapper member 22, formed of a spring strip as shown in Fig. 7, is fastened at its lower end to the bottom of the housing, as shown at 23. The upper end of the member 22 is bent forwardly, as shown at 24 and terminates in a lip 25 for engagement by the projections 17 of the wheel 16. Adjacent the part 24 the strip is bowed outwardly as shown at 26. As will be seen when the lip is engaged by a projection, the strip will be lifted until the lip frees 55

itself from the projection and then the strip will snap back against the bottom of the housing and thus make a clapping noise. A spring 27 resiliently holds the member 18 in lowered position with its part 21 in the path of movement of the projections on the wheel 16.

When the window is to be locked, the housing is placed in the channel member 1 and said housing is adjusted in the member to place the finger 20 adjacent the top rail of the lower sash as shown in Fig. 1. This figure shows the two sashes entirely closed but if it is desired to have the sashes, or one sash, partly opened for ventilating purposes, the housing is adjusted in the channel member to a position where the finger will be engaged by the lower sash if an attempt is made to open either sash to a greater extent. Of course the spring of the motor must be wound up by turning the shaft 8 by the handle member 9. Then if an attempt is made to move either sash, the finger 20 will be engaged by the top rail of the lower sash and this will slide the brake member 18 upwardly which will move the part 21 out of the path of the projections on the wheel 16 and then the wheel will be rotated from the spring motor. During this rotary movement of the wheel 16 the projections 17 thereon will engage the clapper member and alternately lift it and then release it so that the member striking the bottom of the casing will make a clapping noise and thus indicate to a person in the building that an attempt is being made to open the window. If the attempt continues a part of the housing will engage the top rail of the lower sash and this will prevent further opening movement of either sash.

Thus I have provided a simple device which will not only act as a sash lock but it will also sound an alarm to notify occupants of a building that an attempt is being made to enter the building.

It is thought from the foregoing description that the advantages and novel features of the invention will be readily apparent.

It is to be understood that changes may be made in the construction, combination and arrangement of the several parts, provided such

changes fall within the scope of the appended claims.

What I claim and desire to protect by Letters Patent is:—

1. A device of the class described, comprising an elongated channel member attached to a side rail of an upper sash, the flanges of said channel member being turned inwardly, and said member having transverse slots therein, a housing having a flanged base sliding in the channel member, a projection at the upper end of said base for engaging the slots for holding the housing in adjusted position, said flanged base having a loose fit in the channel member for enabling the projection to be moved out of a slot, said housing having a part for engagement by a part of a sash for preventing opening movement of either sash, and means carried by the housing and actuated by movement of either sash for sounding an alarm before movement of a sash is prevented by said part. 5 10 15

2. A device of the class described comprising an elongated channel member connected with a side rail of an upper sash and having its flanges turned inwardly, said member having 25 vertically spaced transverse slots therein, a housing having flanges engaging the flanges of the member for sliding movement, said housing being removable from the member, a catch on the housing for engaging the slots for holding 30 the housing in adjusted position in the member, a spring motor in the housing, a member rotated by the motor and having projections thereon, a brake member slidably arranged in the housing, yieldable means for holding the brake 35 member against the rotary member, a finger on the brake member engaged by a part of a lower sash when either sash is moved towards open position, for releasing the rotary member from the brake member, a part of the housing engaging the lower sash after the brake member has been moved to releasing position, to stop further movement of either sash and a spring clapper member actuated by the projections on the rotary member when the member is rotating. 40 45
